UNITED STATES PATENT OFFICE.

FRED Y. MCKENNEY, OF CHATTANOOGA, TENNESSEE, ASSIGNOR TO THE KELLY MANUFACTURING COMPANY, OF CHATTANOOGA, TENNESSEE, A CORPORATION OF TENNESSEE.

MIXING DEVICE.

Application filed November 1, 1924. Serial No. 747,346.

My said invention relates to a mixing device and it is an object of the same to provide a device of this character which shall be adapted to mix washing powder or other powder whether soluble or insoluble with water or other liquid in any desired proportions.

A further object of the invention is to provide a device of this character which shall not be liable to clog whether by premature wetting of the powder or for other reasons.

Another object of the invention is to provide a device of this character in which the action may be varied according to the nature of the material or objects to be operated on.

Figure 1 is a vertical central section of my device,

Figure 2, a horizontal section on line 2—2 of Fig. 1,

Figure 3 a similar section on line 3—3 of Fig. 1, and

Figure 4 a section on line 4—4 of Figure 1.

In the drawings reference character 10 indicates the outer casing of my device here shown as having an integral bottom and a removable top 11. A shaft 12 is mounted centrally of the device in bearings at the top and bottom, the latter part being pierced for this purpose to receive a flanged sleeve 13 having internal screw-threads by which a nut 14 is adjustably supported. The nut 14 is hollow and has a roller bearing 15 on which the shaft 12 is supported.

A hub 16 is secured to the shaft 12 and carries a sleeve 17 closing the joint between the hub and the sleeve 13. The hub 16 supports a propeller in the form of a horizontal wheel having spokes or vanes 18 carried by an annular rim 19 and an upper horizontal flange 20 on the rim. The rim is supported on the hub by means of spokes 21 each of which is pitched like the vanes of a fan.

Above the propeller a baffle plate 22 is supported on the casing 10 by means of an annular flange 23 riveted or otherwise attached to the casing, the plate being in the form of a cone or, strictly speaking, a frustum of a cone. A number of holes 24 are arranged in a circle on the baffle plate, this arrangement of course to be subject to variation as desired. Above the baffle plate a

similar conical plate 25 is attached to the 55 casing, this plate being the lower member of a storage bin or compartment 25' for the reception of powder. A reversely located conical member 26 is secured to the shaft adjacent to the lower end of the plate 25. The 60 parts 23, 25 and 26 are in effect flanges which might be formed integral with the casing, if preferred. The cone 26 has a spring 27 secured to it in a position to scrape the lower edge of plate 25 while the plate 65 has a spring 28 secured to it and bent so as to scrape the surface of member 26 near the lower edge thereof. The purpose of the springs is to prevent choking and interruption of the feed of powder. The member 26 70 is provided on its upper face with spiral hobs 26' to feed the powder.

Above the plate 25 the shaft 12 has a hub 29 secured thereto from which a plurality of arms 30 radiate. These arms serve as agitating means to keep the powder stirred up in the compartment so that it will feed readily out of the same at the bottom. The top of the casing carries a compartment 31 with in which there is a hub 32 on the shaft 12. 75 Weights 33 are pivotally mounted on the hub 32 and are normally drawn inward by springs 35. When the speed of the machine reaches a predetermined limit the weights fly out under the action of centrifugal force 80 and are adapted to engage the sides of the compartments 31 and act as brakes to retard the shaft 12 and prevent excessive speed of operation. A graduated knob 34 is located at the top of the shaft 12, the purpose being 85 to provide an indicator by observation of which the attendant can determine whether or not the device is running and at what speed. The top 11 may be so constructed as to close the casing but preferably it will consist merely of the compartment 31, a pair of oppositely extending arms 36 and flanges 37 depending from the arms, said flanges fitting closely against the walls of the casing.

The casing is provided with an opening at one point with which a pipe 38 communicates said pipe having a valve 39 by operation of which water can be admitted into the casing when desired. When this is done the propeller will be operated and will turn the shaft 20 to cause rotation of the cone 26 and the stirrers 30 as well as the centrifugal

brake shoes 33. The powder in the upper chamber is stirred and gradually passes out between the cones 25 and 26 assisted by the hobs 26', the springs 27 and 28 scraping the 5 lower ends of the respective parts to prevent choking of the feed. The powder falls into the lower cone 22 and passes thence to the bottom of the casing where it is mixed with the agitated water after which the mixture 10 emerges through the outlet 40. At this time a small quantity of water can splash up through the openings 24 to wash down the inside of the plate 22 and prevent powder from adhering thereto. If hot water is used 15 the vanes 21 draw the steam down out of the casing by creating a downward air current toward the outlet 40. If this were not done the steam might wet the powder in the upper part of the casing to such an extent as 20 to interrupt the feed.

Should the hub 34 stand still at any time the attendant will be notified by the stationary condition of knob 34 that the action of the device has been interrupted for some 25 reason and if necessary will operate it manually by turning the hub. Should there be a tendency to work too fast the centrifugal brake shoes will fly out and slow down the movement of the shaft 12.

30 If it is desired to change the ratio of powder and liquid the nut 14 is turned by means of the stem 41 and thereby the shaft 12 is raised or lowered which either increases or decreases the space between the cones 25 and 26 to cause more or less powder to pass through for each revolution of the shaft. Preferably a scale is provided on the outside of the casing at 42 and the arm 41 is provided with an indicator 43 coacting with 35 the scale to indicate the position of the arm relative to the casing and thereby the position of the cone 26 relative to the cone 25.

It will be obvious to those skilled in the art that various changes may be made in my 45 device without departing from the spirit of the invention and that it may be put to other uses; therefore I do not limit myself to what is shown in the drawings and described in the specification but only as indicated in the appended claims.

Having thus fully described my said invention, what I claim as new and desire to secure by Letters Patent is:

55 1. A mixing device for powder and liquid comprising a casing having a storage space, means to provide a flow of liquid below the powder chamber, means for feeding powder from the storage space to the liquid, including agitating means at the bottom of the chamber and agitating means at a distance from said bottom, and means operated by the flowing liquid to vary the feed of powder in accordance with the rate of flow, substantially as set forth.

60 2. A device for mixing powder and a

fluid comprising a casing, a powder compartment in the casing, means for creating a flow of fluid through the casing below the powder chamber, means for feeding the powder into the fluid, and means for varying said feed independently of such flow, substantially as set forth. 70

3. A device for mixing powder and liquid comprising a casing, a storage compartment for powder in the upper portion of 75 the casing, an inlet whereby water under pressure may be admitted to the casing, means operated by the current of water entering the casing for feeding the powder into the water, and means for withdrawing 80 vapor from the casing, substantially as set forth.

4. A device for mixing powder and liquid comprising a casing, a storage compartment for powder in the upper portion of 85 the casing, an inlet whereby water under pressure may be admitted to the casing, a propeller operated by the water entering the casing, means operated by the propeller for variably feeding powder from the compartment to the water in accordance with the speed of the current, and means operated by said propeller for withdrawing vapor from the casing, substantially as set forth. 90

5. A device for mixing powder and liquid 95 comprising a casing, a shaft therein, a storage space for powder in an elevated part of the casing, a propeller in the lower part of the casing, means for admitting a current of liquid into the casing said current 100 operating said propeller, and means operated by said propeller for feeding said powder from the storage space into said current, substantially as set forth.

6. A device for mixing powder and liquid 105 comprising a cylindrical casing, an upright shaft therein, a storage space about the shaft at the upper end of the casing, a propeller on the shaft adjacent its lower end, means whereby a current of liquid is admitted into 110 the casing for operating the propeller, and means on said shaft for feeding powder into said current, substantially as set forth.

7. A device for mixing powder and liquid 115 comprising a cylindrical casing, an upright shaft therein, a storage space about the shaft at the upper end of the casing, a horizontal wheel on the shaft adjacent its lower end, means whereby a current of liquid is admitted into the casing for operating the wheel, means on said shaft for feeding powder into 120 said current, and a conical plate secured to the casing and extending inwardly therefrom to prevent lodgment of the powder on the outer parts of the wheel, 125 substantially as set forth.

8. A device for mixing powder and liquid comprising a cylindrical casing, an upright shaft therein, a storage space about the shaft at the upper end of the casing, a propeller 130

on the shaft adjacent its lower end, means whereby a current of liquid is admitted into the casing for operating the propeller, means on said shaft for feeding powder into said current, and a conical plate secured to the casing said plate extending inwardly therefrom to prevent access of the powder to the outer part of the propeller and having apertures near its periphery to admit liquid for

10 cleaning the plate, substantially as set forth.

9. A device for mixing powder and liquid comprising a cylindrical casing having a storage space, an upright shaft in the casing, an inverted conical member fitting within 15 the casing and open at its lower end, an upright conical member on the shaft partially closing the opening in the first-named conical member said members forming a bottom for the storage space, and means for admitting liquid to the casing below said conical members whereby powder may flow from the storage space into the liquid, substantially as set forth.

10. A device for mixing powder and liquid comprising a cylindrical casing having a storage space, an upright shaft in the casing, an inverted conical member fitting within the casing and open at its lower end, an upright conical member on the shaft partially closing the opening in the first-named conical member said members forming a bottom for the storage space, and means for admitting liquid to the casing below said last-named conical member having hobs on 30 its upper surface, substantially as set forth.

11. A device for mixing powder and liquid comprising a cylindrical casing having a storage space, an upright shaft in the casing, an inverted conical member fitting within 40 the casing at the lower end of said storage space, said member being open at its lower end, an upright conical member on the shaft partially closing the opening in the first-named conical member, means operating in the space between said members to cause the powder to flow freely, and means for admitting liquid to the casing below said conical members whereby powder may flow from the storage space into the liquid, substantially as set forth.

12. A device for mixing powder and liquid comprising a cylindrical casing having a storage compartment, an upright shaft therein, an inverted conical member fitting within 55 the casing and open at its lower end, an upright conical member on the shaft partially closing the opening in the first-named conical member and coacting therewith to form a bottom for the storage space, resilient 60 scrapers attached to the respective conical members and operating in the space between them, and means for admitting liquid to the casing below said conical members whereby powder may flow from the storage space into the liquid, substantially as set forth.

13. A device for mixing powder and liquid comprising a cylindrical casing, an upright shaft therein, an inverted conical member fitting within the casing and open at its lower end, an upright conical member on the shaft partially closing the opening in the first-named conical member and cooperating therewith to form a bottom for the storage space, means for admitting liquid to the casing below said conical members whereby 70 powder may flow from the storage space into the liquid, and means for adjusting the shaft in the direction of its length to vary the feed of powder, substantially as set forth.

14. A device for mixing powder and liquid comprising a cylindrical casing, an upright shaft therein, an inverted conical member fitting within the casing and open at its lower end, an upright conical member on the shaft 80 partially closing the opening in the first-named conical member and cooperating therewith to form a bottom for the storage space, and means for adjusting the shaft in the direction of its length to vary the feed of powder, substantially as set forth.

15. A device for mixing powder and liquid comprising a cylindrical casing, an upright shaft therein, an inverted conical member fitting within the casing and open at its lower end, an upright conical member on the shaft partially closing the opening in the first-named conical member, means for admitting liquid to the casing below said conical members whereby powder may flow 90 from the storage space into the liquid, and means for adjusting the shaft in the direction of its length to vary the feed of powder, substantially as set forth.

16. A device for mixing powder and liquid comprising a cylindrical casing, a rotary upright shaft therein, an inverted conical member fitting within the casing and open at 100 its lower end, an upright conical member on the shaft partially closing the opening in the first-named conical member, said members forming the bottom of a storage chamber and means for admitting liquid to the casing below said conical members whereby powder may flow from the storage space into the liquid, substantially as set forth.

17. A device for mixing powder and liquid comprising a cylindrical casing, a rotary upright shaft therein, an inverted conical member fitting within the casing and open at its lower end, an upright conical member on the shaft partially closing the opening in the first-named conical member, said members forming the bottom of a storage space, means for admitting liquid to the casing below said conical members whereby powder may flow from the storage space into the liquid, and indicating means on the upper 115 120 125 130

end of the shaft outside the casing rotating with the shaft, substantially as set forth.

18. A device for mixing powder and liquid comprising a cylindrical casing having a powder compartment, a rotary upright shaft therein, an inverted conical member fitting within the casing and open at its lower end, an upright conical member on the shaft partially closing the opening in the first-named conical member, a water wheel at the lower end of the shaft, means for admitting water to operate the wheel and so feed the powder out of said compartment, substantially as set forth.
19. A device for mixing powder and liquid comprising a cylindrical casing, a rotary upright shaft therein, an inverted conical member, said members forming the bottom of a storage space fitting within the casing and open at its lower end, an upright conical member on the shaft partially closing the opening in the first-named conical member, means for admitting liquid to the casing below said conical members whereby powder may flow from the storage space into the liquid, and means to limit the speed of the shaft, substantially as set forth.
20. A device for mixing powder and liquid comprising a cylindrical casing having a powder compartment, a rotary upright shaft therein, an inverted conical member fitting within the casing and open at its lower end, an upright conical member on the shaft partially closing the opening in the first-named conical member, a water wheel at the lower end of the shaft, means for admitting water to operate the water wheel and feed the powder from said compartment, and means on the shaft to withdraw vapor from the casing, substantially as set forth.
21. A device for mixing powder and liquid comprising a cylindrical casing having a powder compartment, a rotary upright shaft therein, an inverted conical member fitting within the casing open at its lower end, an upright conical member on the shaft partially closing the opening in the first-named conical member, a water wheel at the lower end of the shaft, means for admitting water to operate the water wheel and feed the powder from said compartments, and means for adjusting the shaft longitudinally to vary the feed of powder, substantially as set forth.

22. A device for mixing powder and liquid comprising a cylindrical casing having a compartment for powder, a rotary upright shaft therein, an inverted conical member fitting within the casing open at its lower end, an upright conical member on the shaft partially closing the opening in the first-named conical member, a water wheel at the lower end of the shaft, means for admitting water to operate the wheel and feed the powder from said compartments, means for adjusting the shaft longitudinally to vary the feed of powder, a scale on the outside of the casing, and indicating means movable with the shaft adjusting means and coacting with said scale to indicate the vertical position of the shaft, substantially as set forth.

23. In a device of the character described, a casing, a rotary shaft therein, an annular flange on the shaft, a flange on the casing coacting therewith to provide a bottom for a storage space for powder, and stirring means acting between the adjacent edges of said flanges, substantially as set forth.

24. In a device of the character described, a casing, a rotary shaft therein, an obconical plate on the casing, a cone fixed to the shaft providing with said plate the bottom of a storage space for powder, and stirring means acting between the contiguous edges of the parts of said bottom, substantially as set forth.

25. In a device of the character described, a casing, a rotary shaft therein, an annular flange on the shaft, a flange on the casing coacting therewith to provide a bottom for a storage space for a fluent solid, and stirring means carried by one flange acting on the other adjacent to its free edge, substantially as set forth.

26. In a device of the character described, a casing, a rotary shaft therein, an annular flange on the shaft, a flange on the casing coacting therewith to provide a bottom for a storage space for a fluent solid, and stirring means fixed for relative movement with one of said flanges in position to scrape the powder from the other, substantially as set forth.

In witness whereof, I have hereunto set my hand and seal at Chattanooga, Tennessee, this 26th day of March, A. D. nineteen hundred and twenty-four.

FRED Y. MCKENNEY. [I. S.]
